[57] CLAIM

The ornamental design for illuminable address sign, as shown and described.

DESCRIPTION

FIG. 1 is a front elevational view of an illuminable address sign showing our new design, with the broken line showing for illustrative purposes only and forming no part of the claimed design;

FIG. 2 is a top plan view thereof, with the cord broken away to indicate indeterminate length;

FIG. 3 is a left side view thereof, the right side view being identical thereto;

FIG. 4 is a bottom view thereof;

FIG. 5 is a rear view thereof; and,

FIG. 6 is a reduced front elevational view thereof with the broken-line showing for illustrative purposes only and forming no part of the claimed design.
